[57] ABSTRACT

A chemical vapor deposition reactor produces deposits which are uniform in composition and thickness by minimizing convective currents in the immediate vicinity of the substrate. Heating of the substrate, positioning the substrate to face in a downward direction at the upper extremity of an essentially convection-free zone, and a radiation shield are utilized.

CHEMICAL VAPOR DEPOSITION REACTOR

BACKGROUND OF THE INVENTION

1. Field of the Invention

The invention is concerned with the deposition of films on substrates, the substance of the film being produced by a chemical reaction involving a gaseous phase.

2. Description of the Prior Art

Chemical vapor deposition (abbreviated in the following as CVD) is a method of plating solid objects in which deposits are produced by chemical reactions near, at, or on the surface of a substrate. The method involves the introduction of one or more gaseous reactants into the vicinity of a substrate where the substance to be deposited is produced by a change in chemical state such as a breakdown or a combination of reactants. CVD has found a variety of commercial applications; examples are the metallization of mirrors, the pigmentation, reinforcing, protection, and decoration of surfaces, and the manufacture of semiconductor devices and integrated circuitry. CVD can be used to deposit elemental substances as well as chemical compounds such as bromides, carbides, nitrides, oxides and silicides. Deposited films may be amorphous, polycrystalline, or epitaxial and they may be electrically insulating, semiconducting, or conducting. A survey of fundamentals, techniques, and applications of CVD is given in C. F. Powell et al (Ed.), *Vapor Deposition*, John Wiley and sons, Inc., 1966.

In many applications of films deposited by CVD the uniformity in thickness and composition of the deposit is a major concern; this is the case, for instance, with deposited films as they are used in the semiconductor industry. One apparatus designed to produce films of superior uniformity is the CVD device proposed in F. H. Nicoll, "The Use of Close Spacing in Chemical-Transport Systems for Growing Epitaxial Layers of Semiconductors," *Journal of the Electrochemical Society*, Vol. 110, November 1963, pp. 1165-1167, where the source material is placed parallel to and at close range of the substrate. However, the design of this device limits its use to solid source materials and does not allow for the introduction of gaseous reactants.

SUMMARY OF THE INVENTION

The invention represents a chemical vapor deposition reactor which, by minimizing convective currents in the vicinity of the substrate, produces films of superior uniformity.

Convection is prevented (1) by positioning the substrate at the upper boundary of the zone into which gaseous reactants are introduced, (2) by orienting the substrate to face in a downward direction, (3) by uniformly heating the substrate and the gases from above, and (4) by utilizing a radiation shield between the manifold through which gaseous components are introduced and the zone in the immediate vicinity of the substrate.

BRIEF DESCRIPTION OF THE DRAWING

The FIGURE is a cross sectional view of an embodiment of the invention.

DETAILED DESCRIPTION

THE DRAWING

The FIGURE shows enclosure 1 containing substrate support 2 equipped with heater 3 and shown as supporting substrates 4 which face in a downward direction. Auxiliary peripheral heater 5 helps to maintain a uniform temperature distribution in the vicinity of the substrates. Perforated radiation shields 6 and 7 protect inlet manifold 8 from thermal radiation emanating from support 2 and substrates 4. Reactant gases 9 pass upward through the perforated radiation shields 6 and 10 and diffuse upward across the essentially convection-free vicinity of substrate 4. Residual product gases 10 diffuse across the vicinity of substrate 4 in a downward direction and leave the reactor.

Substrate support 2 is a stainless steel plate equipped 15 with a cavity 21 which is partly filled with sodium 22, evacuated, and sealed. Cavity 21 contains one or more pieces of wire mesh 23 in contact with the ceiling and the bottom of cavity 21. Under the influence of heat emanating from heater 3, sodium 22 liquefies, rises by 20 capillary action along wire mesh 23 to the ceiling of cavity 21, evaporates, and condenses again at the bottom of cavity 21.

Operational Principles

The invention achieves uniformity of deposition 25 through minimization of convection in the vicinity of the substrate. This minimization is accomplished by maintaining the substrate at an elevated temperature relative to the introduced reactant gases and by positioning it to face in a downward direction thus ensuring 30 essentially planar and horizontal isotherms. Heating of the substrate may be accomplished by a variety of means, the key requirement being the uniformity of temperature at the surface of the substrate. One heater design which has been particularly effective in assuring 35 uniform substrate temperature encompasses a so-called "heat pipe" integral to the substrate support. In this design, a stainless steel plate supports the substrate and contains an evacuated and sealed cavity which is partly filled with a heat transfer medium such as liquid sodium. Pieces of wire mesh are placed inside the cavity in contact with the ceiling as well as the bottom of the cavity to serve as a wick along which, through capillary action, the heat transfer medium reaches the top of the cavity. Alternately, steel wool, fiberglass, or an equivalent 40 could be used instead of wire mesh. The heat transfer medium evaporates at the heated ceiling of the cavity and condenses at the cooler lower end of the cavity, efficiently transferring heat in a downward direction.

Unless the width-to-height ratio of the zone between 50 the radiation shield and the substrate is very large, peripheral heat and reactant losses should preferably be guarded against. In an experimental embodiment of the invention in which this ratio was about 6:1, peripheral heat loss was compensated by auxiliary heating from a heater tape wrapped around the reactor whose enclosure had a circular horizontal cross section. Depending 55 on the application, differently shaped enclosures may be advantageous.

In order to prevent premature heating of the entering 60 gases as they pass through the inlet manifold, a radiation shield is placed between the substrate and the inlet manifold. The shield protects the inlet manifold from thermal radiation emanating from the substrate and its support and helps prevent forced convection in the vicinity of the substrate. For this purpose the experimental embodiment utilizes a pair of gold plated fused quartz plates placed about 4 millimeters apart. The 65

plates are perforated and positioned relative to each other so that entering gases follow a tortuous rather than a straightthrough vertical path before reaching the vicinity of the substrate. While the experimental embodiment utilizes a pair of plates as a radiation shield, the use of only one or of more than two such plates is not precluded.

During deposition, reactant gases diffuse upward from the radiation shield. At the surface of the substrate reactants are consumed and products created by the deposition reaction. The residual gaseous products in turn diffuse downward and away from the vicinity of the substrate through the radiation shields. The inlet manifold, located in the convection zone below the radiation shields, supplies fresh gases, preferably in a uniform, periodic array of jets to the underside of the radiation shields. The incoming gases dilute the product gases which are forced out the bottom of the reactor; typical gas flow and deposition rates are shown in the examples below.

EXAMPLE 1

Silicon dioxide was deposited onto silicon and tungsten metallized silicon at a temperature of 720°C according to the chemical reaction

using helium as a carrier gas. Flow rates were 1.5 cm³/min for SiH₄, 187.5 cm³/min for N₂O, and 91 cm³/min for helium. Under these conditions a deposition rate of 0.8 micrometers per hour was realized. Variation in thickness of the deposited layer, measured with a spectrophotometer, was found to be no more than 4 percent over the 1½ inch diameter silicon wafers. This compares favorably with variation of up to 10 percent resulting from the use of commercially available apparatus.

EXAMPLE 2

Silicon nitride was deposited onto stainless steel at a temperature of 720°C according to the chemical reaction

using helium as a carrier gas. Flow rates were 1.5

45

cm³/min for SiH₄, 110 cm³/min for NH₃, and 91 cm³/min for helium. A deposition rate of 1.2 micrometers per hour was achieved.

What is claimed is:

1. Chemical vapor deposition apparatus for depositing a layer of a substance on a surface of a substrate comprising

means for supporting said substrate,
means for introducing at least one gas producing said substance into a zone adjacent to said surface,
means for extracting any residual gaseous material, and

means for uniformly maintaining said substrate at a temperature higher than that of said introduced gas characterized in that

1. said surface generally defines the upper extremity of said zone,
2. said surface faces in a downward direction,
3. the lower extremity of said zone is generally defined by a radiation shield permeable to reactant, carrier and product gases, and
4. means are provided for introducing said gas at a position below said radiation shield.

25 2. Chemical vapor deposition apparatus of claim 1 in which said radiation shield consists of at least one perforated plate in a position essentially parallel to said surface of said substrate and of which at least the plate closest to said surface is equipped with a heat-reflecting coating.

3. Chemical vapor deposition apparatus of claim 2 in which said radiation shield consists of a pair of plates separated by a distance of 0.1-10 centimeters.

4. Chemical vapor deposition apparatus of claim 1 equipped with an auxiliary heated positioned at the periphery of the zone between the substrate and the radiation shield.

5. Chemical vapor deposition apparatus of claim 1 in which said supporting means is a heated plate.

6. Chemical vapor deposition apparatus of claim 5 in which said plate is equipped with a heat pipe for transferring heat from the upper to the lower extremity of said plate.
